(57) **CLAIM**

The ornamental design for a tray, as shown and described.

DESCRIPTION

FIG. 1 is a front top right perspective view of a tray showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a front elevational view thereof, shown in a position of use with an exemplary tray.

FIG. 9 is a front elevational view thereof, shown in a position of use with an exemplary tray; and,

FIG. 10 is a bottom perspective view thereof.

The broken lines shown in FIGS. 8 and 9 are shown for the purpose of illustrating environmental subject matter of an exemplary tray and form no part of the claimed design.

1 Claim, 10 Drawing Sheets
